US0D1009882S

(12) **United States Design Patent** (10) Patent No.: **US D1,009,882 S**
(45) Date of Patent: ** Jan. 2, 2024

(54) **DISPLAY SCREEN OR PORTION THEREOF
WITH GRAPHICAL USER INTERFACE**

(71) Applicant: **Delos Living LLC**, New York, NY (US)

(72) Inventors: **Barrett Brod Kaminer**, New York, NY (US); **Max Andrew Pollinger**, New York, NY (US); **Tarynne Blake Lopez**, Cranford, NJ (US); **Dingane Richard St Arromand**, New York, NY (US); **Shivaun Ryan**, South Yarra (AU); **Chris David Hall**, Narre Warren South (AU); **Shaun Benson Stewart**, New York, NY (US)

(73) Assignee: **Delos Living LLC**, New York, NY (US)

(**) Term: **15 Years**

(21) Appl. No.: **29/628,143**

(22) Filed: **Dec. 1, 2017**

(51) LOC (14) Cl. **14-04**

(52) U.S. Cl.

USPC **D14/485**

(58) **Field of Classification Search**

USPC D14/485-495; D20/11; D21/324, 325

Primary Examiner — John M Otte

(74) Attorney, Agent, or Firm — Fitch, Even, Tabin & Flannery LLP

CLAIM

The ornamental design for a display screen or portion thereof with graphical user interface, as shown and described.

DESCRIPTION

The FIGURE is a front view of a display screen or portion thereof with graphical user interface.

The broken line showing of a display screen with graphical user interface is included for the purpose of showing portions of the article which form no part of the claim.

1 Claim, 1 Drawing Sheet
